TRAP SWITCH

Arthur W. Fruh, Chicago, Ill.

Application May 11, 1950, Serial No. 161,463

4 Claims. (Cl. 200—54)

1

The invention relates generally to switch mechanisms, and more particularly to a so-called trap switch for use in burglar alarm systems, or the like.

Trap switches of the type here involved, in the past have generally comprised a stationary contact adapted to be housed in a suitable case or housing which is provided with means for attaching the switch to a wall, or other surface. The casing is provided with an opening in a side wall thereof adjacent the stationary contact, the opening being of a size to receive a relatively movable contact to permit engagement of the later with the stationary contact, such contacts being constructed to frictionally engage one another, whereby they are normally maintained in engaged relation. The movable contact is connected to the free end of a flexible conductor, with the opposite end of the conductor being secured to a terminal enclosed in a suitable casing or housing, and adapted to be mounted on a second surface or object. In use, the switch mechanism above described is inserted in series with a burglar alarm system of the normally closed type, wherein the opening of the circuit at any point will actuate a relay and burglar alarm. Trap switches of this type are particularly useful in applications such as across open doorways, or across storage racks, shelves, or the like, in which case the flexible conductor would be stretched across the doorway or shelf opening. When stretched across a doorway, it is not readily seen, and an intruder thus may strike or kick the cord, withdrawing the movable contact from the stationary contact, and thus actuate the alarm. Likewise, when employed in connection with shelving, etc., the conductor may be stretched across the shelf opening so that articles cannot be withdrawn from the shelf without removing or cutting the cord extending thereacross, again actuating the alarm. Switches of this type are oftentimes employed in connection with alarm systems of the central station type, wherein actuation of the alarm system also actuates an indicator in a central alarm station, such as those operated by various protective associations.

When incorporated in a central alarm system, the trap switch, as well as the other switches in the local burglar system, are provided with additional switch contacts for the closing of the central alarm indicator, and due to the particular types of circuits normally employed, it is especially desirable that the local burglar alarm system be positively actuated prior to the clos-

2

ing of the central alarm circuits. This is particularly true in the case of trap switches, as the frictional connection between the stationary and movable contact is such that a relatively large movement of the movable contact is required before the circuit is actually broken.

The present invention, therefore, has among its objects the production of a trap switch for use in burglar alarm systems, such as that described, wherein the local alarm system is actuated prior to the actuation of the central system, and prior to the separation of the frictionally engaged contacts.

Another object of the invention is the production of such a trap switch, having the above advantages, which is very simple in construction, relatively inexpensive to manufacture, and positive in action.

A further object of the invention is the production of such a trap switch which is provided with a pair of contacts in series with the main contacts of the switch, and adapted to be actuated prior to separation of the main contacts.

Many other objects and advantages of the construction herein shown and described will be obvious to those skilled in the art from the disclosure herein given.

To this end my invention consists in the novel construction, arrangement, and combination of parts herein shown and described, and more particularly pointed out in the claims.

In the drawings, wherein like reference characters indicate like or corresponding parts:

Fig. 1 is a perspective view of a part of a doorway, or the like, illustrating the mounting of a trap switch therein;

Fig. 2 is a longitudinal, sectional view through the movable contact structure employed;

Fig. 3 is a sectional view through a trap switch embodying the present invention taken approximately on the line 3—3 of Fig. 4;

Fig. 4 is a side elevational view of the switch structure illustrated in Fig. 3, with the cover, or housing, shown in section, and the movable contact in engagement with the stationary contact;

Fig. 5 is a view similar to Fig. 4, with the movable contact removed, and illustrating the positions of the other switch elements; and

Fig. 6 is a transverse sectional view taken approximately on the line 6—6 of Fig. 3.

Referring to Figs. 1 and 2, 1 indicates generally a housing enclosing the switch mechanism, including the relatively stationary contact mounted, for example, on a wall surface 2 form-

ing a portion of a hall or doorway. Mounted on the opposite wall 3 is a juncture box 4, and operatively connected thereto at one end is a flexible conductor 5, the opposite end of which is connected to a movable contact structure, indicated generally by the numeral 6. The latter may be engaged with the stationary contact positioned in the housing 1, and operatively connected in series into the burglar alarm system by conductors 7 and 8. Thus, if the conductor cord 5 is struck by a leg, or other object, the movable contact member 6 will disengage the stationary contact and be withdrawn from the housing 1, thereby actuating the alarm.

The movable contact structure 6, is of the usual construction and comprises a tubular sleeve 11, closed at each end by respective plugs 12 and 13 threaded into the sleeve 11. Secured to the plug 12 and extending outwardly therefrom is a shank 14 terminating at its free end in a ball-shaped contact 15, the shank 14 being threaded into the block 12, and locked in position by a nut 16 and lock washer 17. The free end 18 of the conductor 5 is secured to the shank 14 by washer 19 and lock nut 21, the cord 5 extending through a bore 22 in the block 13. Positioned in the sleeve 11 and encircling the cord 5 is a washer 23 and expansion spring 24, the latter seating at one end on the block 13, and at the opposite end on the washer 23, with the last-mentioned end of the spring having coils of reduced diameter to provide effective engagement between spring and washer 23. The conductor 5 is knotted, as indicated at 25, against which the washer 23 bears. In installing the device, as illustrated in Fig. 1, the conductor 5 is made of a length to place the spring 24 under compression when the movable contact 15 is engaged with its cooperable, stationary contact, so that the cord 5 is maintained taut at all times.

The terminal box 4 is of standard construction, and merely provides means for connecting the adjacent end of the conductor 5 to the conductor 8 in the alarm system, at the same time firmly anchoring such end of the conductor; consequently, the details of such juncture box form no part of the present invention.

Referring to Figs. 3 to 6, inclusive, the relatively stationary contact structure includes a base member 26, illustrated as formed of an electrically non-conducting material, on which is mounted a stationary contact 27, the latter, in the embodiment of the invention illustrated, being generally U-shaped in cross section, and having a base portion 28 through which a mounting screw 29 extends, the latter being provided with a cooperable nut 31, thereby firmly attaching the contact 27 to the base member 26. Extending outwardly from the base portion 28 is a pair of oppositely disposed contact arms 32, the vertical edge portions of the arms being bent inwardly slightly, as indicated at 33, to form guiding means for the insertion of the contact 15 between the two arms 32. Each of the latter is provided with an opening 34 therein, the openings being aligned and adapted to receive portions of the ball-shaped contact 15 when the latter is inserted between the two contact arms, as illustrated in Fig. 4. The openings 34 thus form detents tending to retain the movable contact in engaged position, and the contact 27 is constructed of a relatively resilient material whereby it is necessary to slightly spring the two contact arms when inserting the contact 15 therebetween.

Positioned adjacent an open side of the contact 27 is a switch assembly, indicated generally by the numeral 35, illustrated in the present embodiment of the invention as of the leaf type and comprising relatively stationary contact leaves 36 and 37 between which is positioned a movable resilient contact leaf 38. The leaves 36, 37 and 38 are mounted on a series of insulating blocks 39, 41 and 42 secured in position by screws 43 and 44 extending through the base member 26, respective blocks 39, 41 and 42, and leaves 36, 37 and 38, each screw being encircled by an insulating sleeve 45, and threaded on the end of each screw are nuts 46 and 47, respectively, suitable lock washers, or the like, being positioned beneath the respective nuts. Also clamped between the respective blocks and leaves is a pair of terminal strips, the terminal strip 48 being in electrical contact with the leaf 36, and the terminal 49 being in contact with the leaf 41, providing means for connecting conductors 51 and 52 to the respective contact leaves. Carried by the leaves 36 and 38 are respective cooperable contacts 53 and 54, and the free end 20 of the leaf 37 is bent downwardly to provide a contact portion 56 adapted to engage the leaf 38 when in the position illustrated in Fig. 5.

The free end of the movable leaf 38 is provided with extension 57 of a width to be positioned between the contact arms 32 of the stationary contact 27, the portion 57 being enclosed in a sleeve 58 of electrical insulating material. As illustrated in Fig. 4, engagement of the movable contact 15 with the stationary contact 27 will result in engagement of the contact 15 with the extension of the movable leaf 38, moving the latter downward, and bringing the contacts 53 and 54 into engagement. When the contact 15 is withdrawn from the stationary contact 27, the inherent resiliency of the leaf 38 will cause the latter to assume the position illustrated in Fig. 5, thereby engaging the contact portion 56 of the leaf 37. As illustrated in Fig. 3, the conductor 51 is secured at one end to the terminal 48, and thus to the leaf 36, and contact 53 is connected at its opposite end to the stationary contact 27 by means of a terminal strip 59 interposed between the base portion 28 and the base member 26. Likewise, the conductor 52, connected at one end to the terminal strip 49, is connected at its opposite end to a terminal strip 61, and with the bolt 62, nut 63, and washer 64 provides terminal means to which the conductor 1 of the alarm circuit may be connected, the opposite side of the alarm system, of course, being connected to the movable contact 15. As previously described, the contact leaf 37 may be operatively connected to the central alarm circuits by means of a conductor 7 secured to the screw 44 by means of a lock nut 65 and washer 66.

The stationary contact 27 and switch mechanism 35 are enclosed by the housing 1, which is provided with an opening 67 opposite the stationary contact 27, of a size to permit ready entry 65 of the movable contact 15 through the side wall of the housing and engagement with the contact 27, as clearly illustrated in Fig. 4.

In the embodiment of the invention illustrated, the housing 1 is secured to the base member 26 by a bracket 68 having a pair of spaced, substantially parallel leg portions 69 connected by an intermediate base portion 71, the latter being seated upon the base 26 and secured thereto by any suitable means, as for example, rivets 72 passing 75 through the portion 71 and base 26. The leg por-

tions 69 are each provided with an opening 73 therein, each adapted to receive an inwardly extending projection or bead 74 formed in the adjacent side walls of the housing 1, whereby the latter is frictionally held securely in position on the base member 26. Extending across the open face of the base member 26 is a sheet of insulating material 75 held in place by screws 76 passing through the base member 26, and nuts 77. As illustrated in Fig. 3, the screws 76 may be positioned at diagonally opposite corners, with the holes 78 in the other diagonally opposite corners providing means for the reception of screws, or the like, for mounting the device to a wall, or other supporting structure.

In the operation of the device, the alarm circuit conductors 7 and 8 are connected by the conductor 5, contact 15, contact 27, conductor 51, contacts 53 and 54, and conductor 52, so that both the contacts 53 and 54 and contacts 15 and 27 are in series in a circuit. As the contact 15 is withdrawn from the stationary contact 27, outward movement of the contact 15 will permit the movable leaf 38 to move away from the leaf 37 until contacts 53 and 54 separate, this action taking place prior to complete withdrawal of the contacts 15 and separation of the latter with the contact 27. However, upon complete withdrawal of the contact 15, the leaf 38 will move outwardly into engagement with the contact portion 36 of the leaf 37. The central alarm circuit would be connected in series between the leaves 37 and 38, so that upon engagement of the leaf 38 with the portion 36 of the leaf 37, such alarm circuit would be closed to actuate indicating mechanism associated therewith. It will be apparent that, as the contacts 53 and 54 are positioned to open upon relatively slight outward movement of the movable contact 15, the local alarm circuit is immediately actuated, with a delay taking place between actuation of the local alarm circuit and actuation of the central alarm circuit resulting from engagement of the leaves 37 and 38, as the latter circuit will not be closed until the movable contact 15 has been completely withdrawn from the stationary contact 27. Obviously, if the series arrangement disclosed was not employed in the local alarm circuit, it would be difficult to provide the desired delay between the opening of the local alarm circuit and consequent closing of the central alarm circuit.

It will be noted from the above description that I have provided a very simple but efficient trap switch mechanism which provides a desired delay between the actuation of a central alarm circuit following actuation of the local alarm circuit, which trap switch mechanism is simple and durable in construction, very efficient in operation, and inexpensive to manufacture.

Having thus described my invention, it is obvious that various immaterial modifications may be made in the same without departing from the spirit of my invention; hence, I do not wish to be understood as limiting myself to the exact form, construction, arrangement, and combination of parts herein shown and described or uses mentioned.

What I claim as new and desire to secure by Letters Patent is:

1. In a trap switch for burglar alarms, the combination of a generally U-shaped stationary contact, a substantially ball shaped movable contact adapted to be positioned between and frictionally engage the leg portions of said stationary contact, a leaf type switch mechanism 75

including a relatively stationary leaf and a resilient movable leaf, a second pair of cooperable contacts each of which is carried by one of said leaves, said movable leaf extending between the leg portions of said first mentioned stationary contact and engageable with said first mentioned movable contact when the latter is engaged with its cooperable stationary contact operative to normally maintain the second pair of contacts closed, and a third contact leaf related to and adapted to be sequentially engaged by said second movable contact leaf upon the first movable contact being disengaged from its cooperable stationary contact.

15 2. In a trap switch for burglar alarms, the combination of a generally U-shaped stationary contact, a substantially ball shaped movable contact adapted to be positioned between and frictionally engage the leg portions of said stationary contact, a second pair of contacts one of which is movable towards and away from the other contact, means operatively related to said last mentioned movable contact extending between the leg portions of said first mentioned stationary contact and engageable with said first mentioned movable contact when the latter is engaged with its cooperable stationary contact operative to normally maintain the second pair of contacts closed, said first mentioned contacts being electrically connected in series with said second mentioned contacts, and a third contact operatively related to and adapted to be sequentially engaged by said second movable contact when the first movable contact is disengaged from its cooperable stationary contact.

3. In a trap switch for burglar alarms, the combination of an insulating base plate, a housing for enclosing said base plate, a generally U-shaped stationary contact mounted on said base plate, said housing having an opening therein disposed opposite said U-shaped stationary contact, a substantially ball-shaped movable contact adapted to be inserted through the opening in said housing and to be positioned between and frictionally engaged by the leg portions of said U-shaped stationary contact, and a leaf type switch mechanism mounted on said base plate and enclosed within said housing, said switch mechanism including a pair of relatively stationary electrically conductive leaves and a resilient movable electrically conductive leaf, said stationary leaves being disposed on opposite sides of said resilient movable leaf with said resilient movable leaf extending between the leg portions of said first-mentioned stationary contact and engageable by said first-mentioned movable contact upon the latter being inserted into co-operative engagement with said stationary contact, and said resilient movable leaf serving to establish a closed electrical path through one of said stationary leaves upon said movable and stationary contacts being engaged and to sequentially break the same and establish a second closed electrical path through the remaining stationary leaf upon said movable contact being disengaged from said stationary contact.

4. The combination set forth in claim 3 further characterized by conductive means electrically interconnecting said stationary contact and one of said stationary leaves in electrical series relation, a first terminal post mounted on said base plate and electrically connected to the remaining one of said stationary leaves, and a second terminal post mounted on said base plate and electrically connected to said resilient movable

leaf, the entire assemblage being enclosed within said housing.
